DESIGN FOR A BOTTLE

Maurice Chalom, New York, N. Y., assignor to Gloria Vanderbilt Corporation, New York, N. Y., a corporation of New York

Application August 29, 1946, Serial No. 132,945

Term of patent 3½ years

(Cl. D58—6)

To all whom it may concern:

Be it known that I, Maurice Chalom, a citizen of France, residing at New York city, in the county of New York and State of New York, have invented a new, original, and ornamental Design for a Bottle, of which the following is a specification, reference being had to the accompanying drawing, forming part thereof.

In the drawing

Fig. 1 is a front elevational view of a bottle, showing my new design;

Fig. 2 is a side elevational view thereof; and
Fig. 3 is a top plan view thereof.

I claim:

The ornamental design for a bottle, substantially as shown.

M. CHALOM.
